UNITED STATES PATENT OFFICE

EMILE SCHREIBER, OF ATCHISON, KANSAS

RACK

Application filed May 31, 1929. Serial No. 367,364.

This invention relates to a rack and has relation more particularly to a device of this kind especially designed and adapted for use for caps and kindred merchandise, and it is an object of the invention to provide a rack of this character of a revolvable type, together with means whereby the same may be effectively closed or covered to protect the merchandise upon the shelves of the rack or 10 case from dust and the like.

Another object of the invention is to provide a device of this kind comprising a plurality of shelves, said shelves being supported in a manner whereby they can be 15 readily and conveniently removed or applied as the occasions of practice may necessitate.

The invention consists in the details of construction and in the combination and arrangement of the several parts of my improved rack whereby certain important advantages are attained and the device rendered simpler, less expensive and otherwise more 20 convenient and advantageous for use, as will be hereinafter more fully set forth.

25 The novel features of my invention will hereinafter be definitely claimed.

In order that my invention may be the better understood, I will now proceed to describe the same with reference to the accompanying 30 drawings, wherein:—

Figure 1 is a view in elevation of a rack constructed in accordance with an embodiment of my invention, the closing member being partly extended;

35 Figure 2 is a sectional view taken substantially on the line 2—2 of Figure 1;

Figure 3 is a fragmentary vertical sectional view taken through the lower portion 40 of the device as herein disclosed and illustrating the mounting for the rotating rack;

Figure 4 is an enlarged elevational view illustrating in detail the means herein disclosed for holding the shelves in applied 45 position;

Figure 5 is a fragmentary view in side elevation of the structure as illustrated in Figure 4;

50 Figure 6 is an enlarged fragmentary view in top plan illustrating a top mounting for

the roller associated with the closing member;

Figure 7 is an enlarged fragmentary view partly in elevation and partly in vertical section of the structure illustrated in Figure 6;

Figure 8 is a view partly in section and partly in top plan illustrating the connection of the bracket with the upper portion of the casing for the roller;

Figure 9 is a transverse sectional view taken through the roller and the associated casing;

Figure 10 is a fragmentary view in top plan of the upper portion of the rotating rack illustrating the hand hold carried thereby;

As disclosed in the accompanying drawings, B denotes a base of suitable construction and design including a table 1. Extending upwardly from the base a desired distance and positioned centrally of the table 1 is a stationary shaft 2. This shaft 2 is also disposed centrally and axially through a central column C comprised in the structure of the rack proper.

This column C is connected to a circular bottom wall 3 and top wall 4. These walls 3 and 4 are connected by the circumferentially spaced and interposed columns 5, said columns being arranged in series with the columns of each series spaced in a direction 70 radially of the bottom and top walls 3 and 4.

The bottom wall 3 at its central part carries a table 6 which overlies the table 1 and interposed between said tables 1 and 6 is an anti-friction member 7 whereby the rack proper 75 may be readily rotated around the shaft 2. As particularly illustrated in Figure 1, the shaft 2 projects a slight distance above the top wall 4.

The side faces of the columns 5, or of adjacent series of such columns, are provided with the suitable positioned grooves 8 which receive the marginal portions of the horizontally disposed shelves 9. An applied shelf 9 is held against displacement by a swing-

95 ing button 10 pivotally engaged, as at 11, midway its ends with the outer face of an outermost column 5. It is to be noted that each button 10 is of a length to serve as a retaining means for two horizontally adja-

cent applied shelves 9 and when in a vertical position permits a free and unhindered application or removal of a shelf.

The shelves 9 may be of any desired number and of preferred dimensions and each of said shelves affords convenient means for holding a supply of caps or other merchandise, and access may be conveniently had to the various shelves by rotating the rack structure proper as required.

10 The bottom wall 3 carries a depending annular flange 12 positioned adjacent to the periphery of said wall while the top wall 4 carries an upstanding annular flange 14 of the same diameter as the flange 12. The purpose of these flanges 12 and 14 will be hereinafter referred to.

Extending outwardly and radially from the table 1 is a fixed arm 15 while extending outwardly and radially from the upper extended portion of the shaft 2 is a second elongated arm 16, said arms 15 and 16 being vertically aligned. The outer portion of the arm 16 is provided therethrough with an elongated and horizontally disposed slot 17 in which is slidably mounted a bearing block 18. This block 18 has an outstanding arm or shank 19 freely disposed through an opening 20 in the outer end of the arm 16. Positioned within the slot 17 and interposed between the outer end of the arm 16 and the opposed face of the block 18 is an expandible member 21 of desired tension, said member being herein disclosed as a coil spring encircling the arm or shank 19. The tension of this member or spring 21 is such to constantly urge the bearing block 18 inwardly of the arm 16.

Threaded upon the outer or extended end portion of the arm or shank 19 is a wing nut 22. By turning this nut 22 in the requisite direction the resultant contact thereof with the adjacent end of the arm 16 will move the bearing block 18 outwardly or against the tension of the member or spring 21.

15 The lower portion of the block 18 is carried by the inner end portion of the upper arm 23 of a substantially U-shaped bracket, the intermediate or base portion 24 of which being substantially vertically disposed and arranged beyond the outer end of the arm 16. The arm 23 is freely disposed through an opening 25 provided in the outer end of the arm 16 so that the block 18 may have desired sliding movement within the slot 17.

20 The second or lower arm 26 of the bracket has its free end portion provided with a depending flange 27 extending beyond opposite sides of said arm 26.

This flange 27 has close contact with the flange 28 comprised in a slip cap 29 for closing the upper end of a casing 30. The flange 27 is held to the flange 28 by the screws 31 which also engage the wall of the casing 30 to lock the cap 29 in applied position.

25 The outer end portion of the lower arm 15

is formed similarly as that of the arm 16 with the exception that the bracket is upwardly disposed so that the second arm 23 of such bracket is engaged wth a lower slip cap 29. As the sliding bearing block carried by the lower bracket and the associated structure at the outer end of the arm 15 is similar to that hereinbefore described with respect to the bearing block 18 it is not believed necessary that a detailed disclosure of such lower structure be given.

Each of the bearing blocks 18 provides a mounting for a trunnion 32 carried by an end portion of a roller 33 and the outer end portions of the arms 16 or 15 are provided with longitudinally disposed slots 35 through which said trunnion 32 is disposed, said slots 35 being of a length to permit the desired sliding adjustment of a bearing block 18.

Each of the trunnions 32 immediately adjacent to an applied cap 29 has fixed thereto a roller 34 of desired dimensions, the periphery of which being adapted to have frictional contact with an annular flange 3 or 4 so that rotation of the rack proper will result in rotation of the roller 33.

The roller 33 is adapted to have wound thereon or unwound therefrom an elongated flexible member or sheet 36, the same being of a width to bridge the space between the top and bottom walls 3 and 4 and to lap the peripheral portions thereof.

This flexible member or sheet 36 extends through a longitudinally disposed slot 37 positioned in the inner portion of the wall of the casing 30 and said outer end portion of the member or sheet 36 is provided with suitable means whereby the same may be detachably engaged with the rack when it is desired to close the rack. When the outer end portion of the member or sheet 36 is secured to a column 5 rotation of the rack structure in one direction will draw out the member or sheet 36 from within the casing 30 and entirely enclose the rack. In this operation, it is not necessary that the wheels or rollers 34 be in contact with the flanges 12 and 14. However, when it is desired to uncover or open up the rack structure, upon rotation of the rack structure in the requisite direction with the wheels 34 in contact with the flanges 12 and 14 the roller 33 will be rotated in a direction to cause the flexible member or sheet 36 to wind upon said roller 33. With the flexible member or sheet 36 properly wound, upon requisite rotation of the nuts 22 the wheels 34 will be moved away and out of contact with the flanges 12 and 14. Under such conditions it will also be understood that the outer end portion of the flexible member or sheet 36 is disconnected from the rack structure. The flexible member or sheet 36, as herein disclosed, is provided at its outer end with a cross strip 38 possessing a certain degree of inherent flexibility and the extremi-

200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ties of this strip 38 are adapted to be disposed through suitably positioned loop members 39 carried by the walls 3 and 4. The central portion of the strip 38 is provided with a slot 40 through which is adapted to be disposed a turnbutton 41. This button 41 is of a conventional type and carried by the outer edge face of the column 5. The turnbutton 41 together with the loop members 39 provide means whereby the outer end portion of the flexible member or sheet 36 may be detachably engaged with the rack when it is desired to close the rack.

From the foregoing description it is thought to be obvious that a rack constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a rotating rack, a roller supported adjacent to said rack, a flexible member coacting with the roller and adapted to wind thereon and unwind therefrom, said flexible member when unwound serving to enclose the rack, means for connecting the outer end portion of the flexible member to the rack, and means in driving engagement with the rack and the roller for revolving the roller upon rotation of the rack.

2. In combination with a rotating rack, a roller, means for supporting the roller adjacent the rack for movement toward or from the rack, a flexible member winding upon or unwinding from the roller, means for securing said flexible member to the rack, said flexible member when unwound providing means for enclosing the rack, and a wheel rotating with the roller, said wheel when the roller is moved toward the rack contacting with a part of the rack to revolve the roller upon rotation of the rack.

3. In combination, a base, an upstanding stationary shaft carried thereby, a rack rotating upon the base and around the shaft, arms extending from the base and from the shaft above the rack, said arms terminating beyond the rack, bearing blocks carried by the outer end portions of the arms and movable lengthwise thereof, means for moving said bearing blocks, a roller interposed between and rotatably engaged with the blocks, a flexible member winding upon and unwinding from the roller, means for connecting the flexible member to the rack, said flexible member upon rotation of the rack in one di-

rection enclosing the rack, and a wheel rotating with the roller, said wheel frictionally engaging a part of the rack when the bearing blocks are in one position for rotation when the rack is rotated.

4. In combination, a base, an upstanding stationary shaft carried thereby, a rack rotating upon the base and around the shaft, arms extending from the base and from the shaft above the rack, said arms terminating beyond the rack, bearing blocks carried by the outer end portions of the arms and movable lengthwise thereof, means for moving said bearing blocks, a roller interposed between and rotatably engaged with the blocks, a flexible member winding upon and unwinding from the roller, means for connecting the flexible member to the rack, said flexible member upon rotation of the rack in one direction enclosing the rack, a wheel rotating with the roller, said wheel frictionally engaging a part of the rack when the bearing blocks are in one position for rotation when the rack is rotated, brackets carried by the bearing blocks, a casing surrounding the roller and the flexible member wound thereon, said casing being interposed between the brackets, and means for securing the casing to said brackets.

In testimony whereof I hereunto affix my signature.

EMILE SCHREIBER.
